FENCE PROTECTOR

Filed March 21, 1928

Attorney

UNITED STATES PATENT OFFICE.

WALDO E. CALLANE, OF LEBANON, INDIANA.

FENCE PROTECTOR.

Application filed March 21, 1928. Serial No. 263,541.

The object of my invention is to provide a novel fence protector which can be manufactured at small cost and which can be readily attached to a fence and to which the barbed wire strand may be attached in a novel and convenient manner.

I attain these and other objects of my invention by the device illustrated in the accompanying drawings, in which,

10 Figure 1 is a perspective view of the invention in use;

Fig. 2 is a top plan view of the invention; Fig. 3 is a side elevation;

15 Fig. 4 is a detail sectional view on line 4—4 of Fig. 2; and

Fig. 5 is a detail side elevation of another means for attaching the device to a fence post.

Like numerals indicate like parts in each 20 of the several views.

Referring to the accompanying drawings, there is illustrated a conventional fence post 1 having the usual wire strands 2 fixed to them. I provide a fence protector bracket 3 to support the barbed wire strand 9. Member 3 consists of a strip of metal bent at its central portion at an acute angle, or in other words in substantial V-shape, to form the two arms 5 and 6 which are provided with reversely disposed slots 7 near their respective ends, as shown in Fig. 3. The ends are spaced apart so as to engage on opposite sides of a fence post as shown in Figs. 1 and 3. I provide wire rings or clips 8 which are engaged around the wire fence strand 9 and then around the bent metal portion 4 of the fence protector bracket 3.

As shown in Fig. 1 and Fig. 2 the slotted ends of the arms 5 and 6 are engaged on wire strands on opposite sides of the post, thereby holding the bracket in extended position to support the barbed wire strand. The barbed wire strand is fastened to the bent middle portion of the fence protector bracket by

wire clips 4 which are applied in any suitable manner, such as by wire pliers or ringing devices. If it is desired to remove the barbed wire strand this may be readily done by cutting the rings 8 which secure the barbed wire strand to the bracket 3. The device is attached much more readily than with devices in this field heretofore invented.

What I claim is:

1. A fence protector bracket for supporting a barbed wire strand in spaced relation to the rest of the fence, consisting of a single metal strip bent in substantially V-shape, said bracket having reversely positioned slots near the respective ends thereof to engage the wire strands of a fence, said brackets being spaced 55 to engage on opposite sides of the fence post.

2. A fence protector bracket for supporting a barbed wire strand in spaced relation to the rest of the fence, consisting of a single metal strip bent in substantially V-shape, said bracket having reversely positioned slots near the respective ends thereof to engage the wire strands of a fence.

3. In combination with a fence having a plurality of wire strands, an extra strand supporting member consisting of a flat metal bracket in substantially V-shape and having its ends apertured to be secured in a fixed relation to the wire strands and fence post, a barbed wire strand, and means for securing 70 the barbed wire strand to the angular end of the protector bracket.

4. In combination with a fence having a plurality of wire strands, an extra strand supporting member consisting of a metal 80 bracket in substantially V-shape and having its ends adapted to be secured in a fixed relation to the wire strands and fence post, a barbed wire strand, and wire clips securing the barbed wire strand to the end of the fence 85 protector bracket.

WALDO E. CALLANE.
